UNITED STATES PATENT OFFICE

CALVIN LEE FORSYTHE, OF CHICAGO, ILLINOIS, ASSIGNOR OF ONE-HALF TO THOMAS R. DORCEY, OF CHICAGO, ILLINOIS

BANJO MUTE

Application filed December 8, 1927. Serial No. 233,474.

My invention relates to improvements in mutes for banjos and has for one object to provide a combined tail piece and mute for other stringed instruments wherein the mute 5 may be permanently attached to the instrument in place so that the operator may move it into and out of operative position. One of the objects of the invention is to provide a mute which may be assembled with the 10 banjo as an operative part thereof in such position with respect to the hand of the operator that he may be able to move it back and forth into and out of working position without interfering with the tempo of the 15 music. Other objects will appear from time to time throughout the specification and claims.

My invention is illustrated more or less diagrammatically in the accompanying drawings, wherein—

Figure 1 is a plan view;

Figure 2 is a side elevation with parts broken away on an enlarged scale;

Figure 3 is a bottom view of the tail piece 25 with the strings omitted;

Figure 4 is a section along the line 4—4 of Figure 3 with the strings omitted;

Like parts are indicated by like characters throughout the several figures.

30 A is the usual banjo head or drum having a parchment drum surface A¹ held tight on the head. A neck A² projecting from the head terminates in a head A³, having keys A¹³ therein and a bridge A¹⁴. Spaced along 35 the head are the usual frets A⁵.

B is the tail piece mounted on the side of the head opposed to the neck A². This tail piece comprising a metallic plate extends inwardly across the drum. On the outer end 40 of this tail piece are a series of horns B¹. In line with these horns are slots B² terminating toward the forward end thereof in holes B³ therethrough. On the under side of the tail piece are slots B⁴ extending forwardly

45 from the holes. B⁵ are strings having a knot B⁶ engaging the horn B¹. These strings lie in the slots B² pass downwardly through the apertures B³ thence outwardly through the slots B⁴ across the bridge B⁶ and thence across 50 the drum along the neck to the plate A³ where

each string is wound about one of the keys A¹³ so that it can be tightened in the usual manner.

C is a mute comprising a round bar of metal or other suitable, preferably hard, material. 55 This bar is supported at either end by a spring arm C¹ which extends back toward the tail piece. The spring arm is bent to form a loop C² and then inwardly to light on top of the tail piece as at C³ thence bent 60 outwardly and extends beneath the tail piece where the two arms are joined in a central forwardly projecting finger C⁴ which rides in a slot C⁵ on the underside of the tail piece, the purpose of this slot being to guide the 65 arm to hold the spring arms together in line and prevent twisting of the mute on the tail piece and insure that it will be held in such position that it can be moved forwardly and backwardly along the tail piece. C⁶, C⁷ are 70 stops on the tail piece limiting the forward or backward movement as the case may be of the mute. The relation between these stops, the tail piece and the mute are such that when the mute is at the forward extension 75 it rests upon the strings at the point where they engage the bridge. The tension of the spring arm is such that the mute is held snugly against the bridge with sufficient force to prevent dancing or vibration of the mute 80 away from the strings as result of play. When in the inoperative position the mute rests on the tail piece being preferably out of contact with the strings though even if the mute is in contact with the strings at any 85 point between the bridge and the tail piece no particular damage is done because the part of the strings which vibrate and make music is only that part between the bridge and the member A³.

90 Since the mute is guided in its movement along the tail piece and may move into or out of the operative position and since it is permanently mounted as part of the instrument, it will be obvious that the player with 95 a touch of the finger may slide the mute into or out of operative position, thereby making use of the mute or disconnecting its use normally without changing the time of music or the stroke.

I claim:

1. In a stringed musical instrument, a bridge, a tail piece, there being a groove on the underside of the tail piece, a mute adapted when in one position to bear on the bridge comprising a transverse bar, spring arms extending rearwardly therefrom from the tail piece, the arms embracing the tail piece, a member associated with said arms and slid- able in the groove on the underside of the tail piece.
2. In a stringed musical instrument, a bridge, a tail piece, there being a groove on the underside thereof, a mute comprising a transverse bar, spring arms extending rear- wardly from the tail piece, the arms embrac- ing the tail piece, a member associated with said arms and slidabile in the groove on the underside of the tail piece, stops on the tail piece adapted to limit the movement of the mute between two extremes one with the mute in engagement with the strings on the bridge, the other with the mute in engage- ment with the tail piece itself.
3. A tail piece for stringed musical instru- ments comprising a flat plate, a plurality of horns on the rear end, the upper surface there- of being slotted in line with the horns, there being perforations through the plate at the forward ends of the slots and slots on the un- derside of the plate extending from the perforations forwardly to the end of the plate, generally parallel with the slots on the upper side thereof, a channel on the underside of the tail piece, a carriage engaging the tail piece, the bottom thereof having a member slid- able in the channel and a mute carried by the carriage.
4. A tail piece for stringed musical instru- ments having a bridge comprising a flat plate, a plurality of horns on the rear end, the upper surface thereof being slotted in line with the horns, there being perforations through the plate at the forward ends of the slots and slots on the underside of the plate extending from the perforations forwardly to the end of the plate, generally parallel with the slots on the upper side thereof, a channel on the underside of the tail piece, a carriage engag- ing the tail piece, the bottom thereof having a member slidable in the channel and a mute carried by the carriage, spring arms inter- posed between the carriage and the mute and tending yieldingly to press the mute down- ward on the bridge with which the mute when in one position cooperates.

Signed at Chicago, county of Cook and State of Illinois.
